CONTROL MECHANISM FOR POWER SHOVELS

George G. Morin and Emile J. Carleton, Holyoke,
Mass.; said Carleton assignor to said Morin

Application November 19, 1935, Serial No. 50,554

2 Claims. (CL. 192—4)

This invention relates to excavating machinery of the type of shovels, cranes, and scoops, and has particular reference to improved mechanism for swinging the boom by which the shovel is carried. As will be pointed out below, however, the invention is not in all particulars limited to this use, certain features finding applicability to mechanical means for tripping the door at the bottom of the shovel. In one aspect the invention is concerned with giving a better control over the swinging of the boom, particularly with respect to the amount of effort required of the operator in actuating the controls. In another aspect the invention is concerned with mechanism permitting the boom to be swung rapidly and surely to any desired position and then held firmly while the desired excavation or unloading is being accomplished without the necessity of using the reversing mechanism of the swing in order to bring the boom to rest. As is well understood, it is customary to swing the boom by moving not only the boom but the whole cab and operating mechanism as well, giving a considerable weight which it is necessary to bring rapidly to rest when the swing has been completed. For reasons which will appear in detail below the prior practice of using the reversing mechanism for this purpose has entailed a seriously great wear on the parts, which it is one object of the present invention to eliminate. Other objects will appear from the following description and claims.

Referring to the drawings,

Fig. 1 is a transverse sectional view of a driving means for rotating the boom of a power shovel, embodying the present invention;

Fig. 2 is a side view of the brake mechanism through which movement of the boom in one direction is controlled;

Fig. 3 is a similar view of the brake mechanism which holds the boom when the control shaft is in neutral position;

Fig. 4 is a view on a smaller scale showing the general assembly of the steam shovel and controlled parts;

Fig. 5 is a transverse sectional view of a dipper tripping mechanism embodying the present invention;

Fig. 6 is a fragmentary side view of the clutch actuating cams;

Fig. 7 is a sectional view on line 7—7 of Fig. 6 showing the clutch actuating cams in operative position;

Fig. 8 is a view similar to Fig. 7 showing the parts in clutch operating position;

Fig. 9 is an end view of the control cam shaft showing the relative position of the several control cams; and

Fig. 10 and Fig. 11 are views similar to Fig. 7, but showing two alternative forms of interengaging cams.

Referring to Fig. 4, a conventional power shovel is shown comprising a caterpillar carriage 1, upon which is rotatably mounted a cab 2 in which the engine and driving mechanism is mounted. The boom pivoted at its lower end to the cab is indicated at 3 and carries a dipper 4 and dipper stick 5, the latter retractably and pivotally mounted on the boom.

The cab is pivoted on the carriage at 6 and is rotated about said pivot through a stub shaft 10 journaled in the cab frame and provided at its lower end with a pinion 11 meshing with a gear 12 also carried by the cab. A planetary pinion 13 secured to gear 12 engages an internal gear 20 fixed to carriage 1 concentrically with pivot 6 whereby rotation of shaft 10 causes pinion 13 to travel around gear 20 thus turning the cab and the parts carried thereby about pivot 6 in a direction determined by the direction of rotation of shaft 10. This mounting of the cab on the carriage is conventional and need not further be described.

Referring now to Fig. 1, the upper end of stub shaft 10 is shown provided with a bevel gear 8 engaging diametrically opposed bevel pinions 15 and 15' freely mounted on a power shaft 16 which is normally constantly rotating and serves as the source of power to drive shaft 10 in either direction depending on which of pinions 15 or 15' is coupled to power shaft 16. Bushings 17 and 17' are interposed between the pinions and the shaft. As is obvious from Fig. 1 pinions 15 and 15', and the parts associated therewith are similar but reversed and similar parts are given the same reference characters except that the characters to the right as viewed in Fig. 1 are primed. A description of the parts associated with pinion 15 will serve equally for the parts associated with pinion 15'.

Pinion 15 is formed with a flange 18 to which an annular member 19 is secured by bolts 20. An annular disc 21 forming one member of a friction clutch by which pinion 15 is coupled to shaft 16 is mounted on bolts 22 threaded into member 19, the annular member 21 having a slight amount of free play axially of the bolts. Disc 21 extends between opposed clutch members 24 and 25, the faces of disc 21 being pro-

vided with annular friction members 26 secured to disc 21 by rivets 27.

Clutch member 24 is formed integrally with a hub 29 splined at 30 to shaft 16, and positioned between a collar 31 fitting in a groove 32 formed in the shaft and a thrust bearing 33 interposed between the hub and pinion 15. Clutch member 25 is formed with a hub portion 35 rotatably and slidably mounted on hub 29. Members 24 and 25 are connected by pins 36 secured in bosses 37 formed in member 24 whereby both members 24 and 25 constantly rotate with shaft 16, member 25 sliding on hub 29 and pins 36 to frictionally engage disc 21 between the clutch members to thereby couple pinion 15 to shaft 16.

The means for forcing the member 25 toward 24 to engage the clutch comprises two ring members 40 and 41 fitted on hub 29. Member 40 is pinned to hub 35 as at 42. Member 41 is rotatably mounted on the hub 29 but normally partakes of the rotation of ring 40 by engagement of re-entrant cam surfaces 44 and 45 formed in rings 40 and 41 respectively, see Fig. 7. As shown in Fig. 1, hub 35 is undercut at 46 to accommodate cam 44. A nut 47 threaded on hub 29 restrains outward axial movement of the rings. It will be obvious that if a sufficient drag is placed upon ring 41 to restrain its tendency to move with ring 40, cam 44 will advance relative to cam 45 as shown in Fig. 8, and since ring 41 is held against outward movement by nut 47, ring 40 and member 25 to which it is attached are moved inwardly as cam 44 advances along the incline of cam 45, thus engaging clutch member 21 between members 24 and 25 and coupling pinion 15 to the power shaft.

Alternative forms of interengaging cams are shown in Figs. 10 and 11. In the form shown in Fig. 10, cams 44 and 45 are replaced by opposed concave and convex cam members 110 and 111 forming an enclosure for a free cylinder or ball 112. As will be clear, relative movement between ring members 40 and 41 will cause free member 112 to engage the inclined surfaces of members 110 and 111 to separate the ring members, thus engaging the clutch as previously described. The form shown in Fig. 11 is similar in operation, the cam members 114 and 115 in that figure taking the form of elongated curved depressions presenting curved cam surfaces against which a free cylinder or ball 116 operates in the same manner as member 112 in Fig. 10.

To impose the desired drag on ring 41 the latter is provided with a brake drum 50, secured to the ring by rivets 51, against which drum brake shoes 52 (see Fig. 2) operate. Shoes 52 are pivoted at 53 to operating arms 54. Links 55, also pivoted to the shoes at 53 are pivotally connected at 56 to a stationary frame member 57. The operating arms 54 are connected together by a link 59. Separation of the upper ends of arms 54 to move shoes 52 into contact with the drum 50 is effected by a generally diamond-shaped control cam 60 secured on a rock shaft 61. As previously indicated the pinions 15 and 15' and their respective associated parts are mirror images of each other. It should further be noted (see Fig. 9) that control cam 60' is positioned on shaft 61 at an angle with respect to cam 60, so that rotation of shaft 61 to cause application of shoes 52 to drum 50 by cam 60, simultaneously moves cam 60' out of operating relation to arms 54'. Thus shaft 10 may be caused to rotate in the desired direction by rocking shaft 61 to apply appropriate brake 27 or 27'.

Rock shaft 61 is provided with a hand lever 62 or other suitable operating means. Dependent on the extent to which the shaft 61 is rocked a greater or less force will be applied to brake drums 27 or 27' and a correspondingly greater or less degree of slippage between clutch members 57 and 24-25 (or 57' and 24'-25') will take place, thus regulating the speed with which cab 2 and boom 3 are rotated.

As will be clear from Fig. 9, the angle between cams 60 and 60' is such that shaft 61 can be moved to a neutral position in which neither cam is operative to actuate the breaking mechanism and that in this position neither pinion 15 or 15' is coupled to shaft 16, the cam and boom being stationary. For proper operation of the shovel it is desirable that the cab be positively held in its stationary or working position. To accomplish this we provide means to hold one of the pinions 15 or 15' against rotation when shaft 61 is in neutral position. As shown, annular member 19 is provided at its outer periphery with a facing of friction material 65 against which is positioned a brake band 66. The ends of brake band 66 are pivotally connected at 67 to operating arms 68. Arms 68 are respectively pivoted at 69 to parallel links 70 which are pivotally secured at 71 to frame member 57. Pivots 69 are adjustably connected by a turnbuckle 72. The free ends of arms 68 are provided with flanged 30 rollers 75 engaging a control cam 76 secured to shaft 61 and so arranged with respect to cams 60 and 60' that its operative position corresponds to the common neutral position of the latter cams. It will thus be seen that when shaft 61 35 is moved to neutral position upon the completion of a movement of the cab and boom in response to either cam 60 or 60', cam 76 acts to apply brake 66 thus bringing the cab and boom to rest without use of the reversing mechanism and that brake 66 holds the boom in the position to which it is moved. Since normally a positive brake action is desired in neutral position cam 76 is provided with recesses 77 in which rolls 75 40 may seat. Cam surfaces 78 however preferably 45 begin to act before cams 60 or 60' are completely released so that the movement of the boom is always controlled and overrun is prevented.

In order to increase the efficiency of the brake 66 we prefer to make it self-energizing in both 50 directions. We accomplish this by providing slots 63 in the end lugs 34 of the brake band, through which slots extend pins 64 secured in frame member 57. When the brake is in inoperative position as shown in Fig. 3, the pins 64 both 55 engage the ends of the slots adjacent the ends of the band. Assuming that the drum is rotating counterclockwise in Fig. 3, the band 66, when the brake is applied, tends to follow the surface of the drum as the band tightens. Such tendency is 60 restrained at the left hand pin 64 (as viewed in Fig. 3) since that pin is in engagement with what is then the rear end of its slot. The other end of the band however is free to advance from its pin with the result that the brake band tends 65 to wrap itself around the drum due to the motion of the drum. When the drum is to be brought to a stop from a clockwise direction of rotation as viewed in Fig. 3, the action is exactly similar except that the function of the two 70 pins and their slots is reversed.

The control mechanism of this invention may be employed to actuate the dipper trip of the shovel or the tag line of a clam shell bucket if the latter is used. In Fig. 4 the boom is shown 75

equipped with a dipper but the dipper trip cable shown at 79 might for illustrative purposes equally well be the tag line of a clam shell bucket. In either case tension is placed or maintained 5 on cable 79 by winding it on a drum 80, see Fig. 5. As shown drum 80 is freely mounted by means of roller bearings 81 on a stub shaft 82 secured to the end of constantly rotating power shaft 63, which may be shaft 16 previously described. An annular clutch member 84, similar 10 to member 21 previously described, is secured to drum 80 at 85 to extend radially inwardly between clutch members 86 and 87 similar in arrangement and construction to members 24 and 25. Member 86 is formed with a hub portion 88, splined at 89 to shaft 82, member 87 being slidably mounted on hub 88 and pinned to member 86 by means of pins 90 for rotation with and 15 movement toward and from the latter member to thereby couple drum 80 to shaft 82. The means for actuating the clutch member 87 comprises a pair of cam rings 91 and 92 similar to rings 40 and 41. Rings 91 and 92 are respectively provided with normally interengaging cam surfaces 93 and 20 94. Ring 91 is secured to member 87 by rivets or bolts 95 and ring 92 is riveted at 97 to a brake drum 88. Thus any drag placed on drum 88 causes ring 91 to advance with respect to ring 92 causing cam surface to act, as illustrated in 25 Fig. 8 with respect to rings 40 and 41, to move clutch member 87 into engaging position. The clutch parts are held in assembled relation by a nut 100 threaded on hub 88, a coil spring 101 being positioned between nut 100 and ring 91 to 30 maintain sufficient pressure on the clutch members so that no slack forms in the trip cable or tag line connected to drum 80.

Drag is applied to drum 88 for actuation of the clutch by brake means indicated at 103 which 35 means may be exactly similar to that employed with drum 50 and therefore needs no further description.

We claim:

1. Means for controlling the rotation of a power 40 shovel cab on its carriage which comprises, a shaft for rotating the cab, a bevel gear on said shaft, a constantly driven power shaft, two bevel pinions freely rotatable on the power shaft and engaging the bevel gear on opposite sides of said 45 cab rotating shaft, a friction clutch member connected with each bevel pinion, friction clutch members secured to the power shaft and respectively engageable with the first mentioned clutch members for coupling said pinions to the

power shaft, a pair of interfitting cam members associated with the power member of each clutch and normally rotatable therewith, one of said cam members being secured to said power member, the second cam member normally rotating with the first cam member by its interengagement therewith and brake means operating on the second cam member to cause relative angular displacement between the cam members to effect engagement of the associated clutch members, the degree of engagement of the clutch members varying with the force of the application of the 5 brake, a rock shaft, a cam on said shaft for actuating one of said clutch actuating brakes when the rock shaft is rocked in one direction, and a cam on said shaft to actuate the other said clutch actuating brake when the rock shaft is rocked in the opposite direction.

2. Means for controlling the rotation of a power shovel cab on its carriage which comprises, a shaft for rotating the cab, a bevel gear on said shaft, a constantly driven power shaft, two bevel pinions freely rotatable on the power shaft and engaging the bevel gear on opposite sides of said cab rotating shaft, a friction clutch member connected with each bevel pinion, friction clutch members secured to the power shaft and respectively engageable with the first mentioned clutch members for coupling said pinions to the power shaft, a pair of interfitting cam members associated with the power member of each clutch and normally rotatable therewith, one of said cam members being secured to said power member, the second cam member normally rotating with the first cam member by its interengagement 20 therewith, and brake means operating on the second cam member to cause relative angular displacement between the cam members to effect engagement of the associated clutch members, the degree of engagement of the clutch members varying with the force of the application of the 25 brake, a rock shaft, a cam on said shaft for actuating one of said clutch actuating brakes when the rock shaft is rocked in one direction, and a cam on said shaft to actuate the other said clutch actuating brake when the rock shaft is rocked in the opposite direction.

GEORGE G. MORIN.
